DESIGN FOR A FOLDABLE TOOTHBRUSH

Samuel Katz, Miami, Fla.

Application May 11, 1945, Serial No. 119,505

Term of patent 14 years

(Cl. D9—2)

To all whom it may concern:

Be it known that I, Samuel Katz, a citizen of the United States of America, residing at Miami, county of Dade, and State of Florida, have invented a new, original, and ornamental Design for a Foldable Toothbrush, of which the following is a specification, reference being had to the accompanying drawing, forming a part thereof, wherein:

Figure 1 is a perspective view of a foldable

toothbrush in closed position, showing my new design;

Figure 2 is a bottom plan view thereof in open position; and

Figure 3 is a side elevational view thereof.

I claim:

The ornamental design for a foldable toothbrush, as shown.

SAMUEL KATZ.
